CLAIM

The ornamental design for a computing device, as shown and described.

DESCRIPTION

FIG. 1 is a front bottom perspective view of a computing device showing our new design;

FIG. 2 is another front perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is an enlarged view thereof, taken from encircled portion labeled as 9 in FIG. 2;

FIG. 10 is a front top perspective view thereof;

FIG. 11 is another front perspective view thereof; and,

FIG. 12 is an enlarged view thereof, taken from encircled portion labeled as 12 in FIG. 11.

The even-length broken lines in the drawings illustrate portions of the computing device that form no part of the claimed design. The dash-dot-dash broken lines in FIGS. 1-5, 7 and 9-12 represent a claim boundary only and form no part of the claimed design. The dot-dot-dash broken lines in FIGS. 2, 9, 11, and 12 are included to show a partially enlarged view only and form no part of the claimed design.
